UNITED STATES PATENT OFFICE.

LIONEL A. CARTER, OF ST. LOUIS, MISSOURI.

LATHE.

Application filed December 3, 1920. Serial No. 428,056.

To all whom it may concern:

Be it known that I, LIONEL A. CARTER, a subject of Great Britain, and a resident of the city of St. Louis and State of Missouri, 5 have invented a new and useful Improvement in Lathes, of which the following is a specification.

This invention relates to lathes and more particularly to the means for closing the 10 feed-nut upon the feed-screw and for releasing it therefrom.

One of the principal objects of the present invention is to provide a simple and efficient means for opening and closing the 15 feed-nuts of lathes which can be easily operated and which, when operated to close the feed-nut about the feed-screw, positively locks the two halves of the feed-nut against separation under internal pressure of the 20 feed-screw thereagainst. Another object is to prevent the closing of the feed-nut upon the feed-screw except in certain positions, thereby preventing operation of both the feed-rod and feed-screw at the same time. 25 Another object is to minimize the pressure of the two halves of the feed-nut on the feed-screw at the beginning of their closing-in movement, thereby preventing injury to the threads and to increase the pressure after 30 the threads of the two half-nuts are in mesh with the threads of said feed-screw.

The invention consists principally in improved means for opening and closing the feed-nut and in means for preventing the 35 operation of the feed-rod and feed-screw at the same time. The invention further consists in the parts and arrangements of parts hereinafter described and claimed.

In the accompanying drawing, which 40 forms part of this specification, and wherein like symbols refer to like parts wherever they occur,

Fig. 1 is a fragmentary inside face view 45 of a lathe apron in the region of the feed-nut, showing the adjacent portions of the feed-screw and feed-rod and a feed-nut controlling device embodying my invention, the feed-nut being shown released from the feed-screw;

Fig. 2 is a view similar to Fig. 1, showing 50 the feed-nut closed upon the feed-screw;

Fig. 3 is a vertical section through the apron on the line 3—3 in Fig. 2; and

Fig. 4 is a horizontal section through the 55 apron on the line 4—4 in Fig. 1.

In the accompanying drawing, 1 indicates

the depending apron portion of an ordinary traveling tool-carriage, which is slidably mounted on the ways of the lathe bed (not shown); 2 indicates the feed-screw for moving the carriage along the lathe bed when thread cutting; and 4 indicates the feed-rod for moving said carriage when doing work other than thread cutting.

The feed-nut comprises upper and lower 65 sections in the form of half-nuts 5 and 6, which are disposed above and below the feed-screw 2 and have vertically disposed plate portions 7 and 8 formed integral therewith. Said half-nuts are arranged for vertical sliding movement toward and away 70 from each other at right angles to the longitudinal axis of the feed-screw. The opposite side marginal portions of the slide plates 7 and 8 of the upper and lower half-nuts 5 and 6 are arranged for vertical sliding 75 movement in angular recesses or rabbets 9 formed in the opposing edges of a pair of vertically disposed horizontally spaced lugs 10 which project outward from the 80 inner face of the apron member 1. The side margin of the slide plates 7 and 8 of the upper and lower half-nuts are retained within the angular recesses 9 of the lugs 10 by means of plates 11 which are secured to 85 the face of the lugs with their inner side marginal portions overlapping the outer side marginal portions of the slide plates, by means of cap screws 12.

The mechanism for separating or bringing 90 the half-nuts together comprises a pair of curved links 13 and 14. The links are disposed one above the other between the disposed spaced lugs 10 of the apron member with the lower end of the upper link 95 13 and the upper end of the lower link 14 adjacent to each other. Journaled in a horizontal bore in the apron member 1, midway between the spaced lugs 10 thereof, and opposite the longitudinal axis of the feed-screw 2 is a rock shaft 15. The outer end of the shaft 15 has a rock handle 16 fixed thereon, and the inner end of said shaft projects through the apron member and has a disk 17 fixed thereon. The lower 100 end of the upper link 13 and the adjacent upper end of the lower link 14 are pivotally mounted on oppositely disposed pins or arbors 18 and 19 which project outwardly from the face of the disk 17 on opposite 110 sides of its center. The upper end of the upper link 13 is pivotally mounted on a

pin or arbor 20, which projects from the face of the slide plate 7 of the upper half-nut 5; and the lower end of the lower link 14 is pivotally mounted on a pin or arbor 21, which projects from the face of the slide plate 8 of the lower half nut 6, the pins 20 and 21 being disposed in vertical alinement.

The operation of bringing together or separating the two halves of the feed-nut is accomplished by a 90 degree turn of the operating handle. When it is desired to close the two halves of the feed-nut upon the feed-screw, for the purpose of using said screw 10 as a means for feeding the carriage, the operating handle is turned to partially rotate the disk 17 in a direction that will cause the pivot 18 to swing downwardly and the pivot 19 to swing upwardly, both pivots swinging 15 in an arc described from the center of said disk. This swinging movement of the pivots 18 and 19, by reason of the link connections 13 and 14 with the pivots 20 and 21 of the two half sections of the feed-nut, 20 causes the two half-nuts to move toward each other and close about the feed-screw. When in this position, the pivots 18 and 19 of the disk 17 and the pivots 20 and 21 of the half-nuts are on a dead center, thus preventing 25 separation of the half-nuts under internal pressure. At the beginning of the closing-in movement of the two half-nuts, the pressure exerted by the half-nuts upon the feed-screw is slight, thereby avoiding 30 injury to the threads, and permitting the half-nuts to properly seat upon the feed-screw before the leverage is increased and the centers of the pivots of the links 13 and 14 coincide. The adjacent end portions of 35 the links 13 and 14, are curved away from each other to enable said portions to clear each other during the swinging movement 40 of the links.

The feed screw 2 is journaled in a bracket 45 22, which projects from the middle portion of the guide plate at the end of the apron, and feed rod 4 is journaled in a bearing 23, which projects from the lower end of said guide plate.

For ordinary work, the tool-carriage is 50 moved by means of the usual rack and pinion feed (not shown), the feed being taken from the feed-rod. Motion is transmitted from the feed rod to a beveled reversing gear 24 through a sliding pinion 25. The reversing gear 24 is journaled in a suitable bearing in the apron member, and the sliding pinion 25 is journaled in a bearing 55 formed integral with the back plate (not shown) of said apron member. Motion is transmitted from the reversing gear 24 to the rack and pinion feed through a train of gears (not shown), the rack gear of said train meshing with the rack on the lathe 60 frame. The sliding pinion 25 is formed in-

tegral with one end of a sleeve 27, which is splined on the feed-rod so as to slide longitudinally thereof and rotate therewith. This sleeve has a tubular extension 28 pinned thereon, which extension is provided near 70 one end with an annular groove 29 adapted to cooperate with a lug 30, which projects horizontally from a depending portion 31 of the slide plate 8 of the lower half of the feed-nut. The opposite end of the tubular 75 extension has a reduced portion which is fitted into the adjacent end of the pinion sleeve 27 and is pinned therein. The shoulder formed by the reduced end portion of the tubular extension is spaced away from the adjacent end of the tubular sleeve 27, forming in connection therewith a second annular groove 32 adapted to receive the lug 33 of a shifter arm 34. With this arrangement, when the sleeve 27 is in neutral 80 position, that is, with the pinion 25 out of mesh with the reversing gear 24, the annular groove 29 of the tubular extension 28 is directly over the lug 30 of the lower half-nut 6, thus permitting the lower half-nut to be 85 raised and the screw drive to be employed. When the rack and pinion drive is desired, the sleeve 27 is shifted to cause the pinion 25 thereof to mesh with the reversing gear 24. This shifting of the pinion sleeve carries the annular groove 29 of the tubular extension 28 from its position over the lug 30 of the lower half-nut 8 and carries the body portion of said extension into position 90 over the lug 30, thus preventing upward movement of the lower half-nut. The screw-feed and the rack and pinion-feed for the tool-carriage may be reversed, the screw-feed being reversed by reversing the direction of rotation of the feed-screw and the 95 rack and pinion-feed being reversed by means of a pinion (not shown) formed on the opposite end of the pinion sleeve 27 and adapted to be thrown into mesh with the opposite side of the reversing gear 24 when the 100 sleeve 27 is shifted in the opposite direction. 105

The hereinbefore described arrangement admits of considerable modification without departing from the invention; therefore, I do not wish to be limited to the exact details 110 of construction shown and described.

What I claim is:—

1. In combination with the feed-screw and the feed-rod of a lathe, and a gear-shifting sleeve slidable on said feed-rod, of a feed-nut comprising a pair of half-sections adapted to be closed upon said feed-screw and to be released therefrom, one of the half-sections of said feed-nut having a portion that projects beyond said feed-rod and has a lateral extension that overlaps said sleeve and lies close to the surface thereof in one position of said sleeve so as to be obstructed thereby but is unobstructed by said sleeve in its opposite position, whereby simultaneous 120

- operation of said feed-screw and said feed-rod is prevented.
2. In combination with the feed-screw and the feed-rod of a lathe of a feed-nut comprising a pair of half-sections adapted to be closed upon and released from said feed-screw, and a sleeve splined on said feed-rod below said feed-nut and adapted to operatively connect said feed-rod with the feed-mechanism of said lathe, said sleeve having an annular groove formed therein, the lower half-section of said feed-nut having a finger extending beneath said sleeve, said finger being adapted in the closed position of said feed-nut to engage the groove in said sleeve to prevent operation of the feed-rod, said finger being adapted in the released position of said feed-nut to engage the body portion of said sleeve and thereby prevent the closing of said feed-nut upon said feed-screw during the operation of said feed-rod.
3. In combination with the feed-screw and the feed-rod of a lathe, and a gear-shifting sleeve slidable on said feed-rod, of a feed-nut comprising a pair of half-sections adapted to be closed upon said feed-screw and to be released therefrom, said sleeve having a portion that moves into and out of the path of a portion of one of said half-nuts, with shifting of the gear, whereby simultaneous operation of said feed-screw and said feed-rod is prevented.

Signed at St. Louis, Missouri, this 30th day of Nov., 1920.

LIONEL A. CARTER.
